DESCRIPTION

FIG. 1 is a top perspective view of an electrode patch array showing our new design;

FIG. 2 is a bottom perspective view thereof;

FIG. 3 is a top view thereof;

FIG. 4 is a bottom view thereof;

FIG. 5 is a side view thereof;

FIG. 6 is a side view thereof;

FIG. 7 is a side view that opposes the side view of FIG. 6; and,

FIG. 8 is a side view that opposes the side view of FIG. 5.

We claim the ornamental design for the electrode patch array, as shown and described.

CLAIM

The broken lines are included for purpose of illustrating portions of the electrode patch array that form no part of the claimed design.
